ATTORNEY

UNITED STATES PATENT OFFICE.

JAY PIERRE BERGERON, OF WASHINGTON, ILLINOIS.

ADVERTISING DEVICE.

1,057,403.

Specification of Letters Patent.

Patented Apr. 1, 1913.

Application filed October 29, 1908, Serial No. 460,110. Renewed December 31, 1910. Serial No. 600,282.

To all whom it may concern:

Be it known that I, JAY PIERRE BERGERON, a citizen of the United States, residing at Washington, in the county of Tazewell and 5 State of Illinois, have invented new and useful Improvements in Advertising Devices, of which the following is a specification.

This invention relates to improvements in advertising devices of that character adapted to be secured to the wheels of a vehicle.

One of the objects of the invention is to provide a support for the advertising card or matter which will effectively support the same and which will at the same time combine 15 the elements of lightness of weight and rigidity necessary for structures of this character.

A further object of the invention is to provide a device of this character of the fewest possible number of parts and of the 20 least possible cost of construction.

The invention will be more fully described in connection with the accompanying drawings and will be more fully set forth and 25 particularly pointed out in and by the appended claims.

In the drawing: Figure 1 is a front view in side elevation of a device embodying the main features of my invention with the advertising card removed. Fig. 2 is a sectional view on line 2—2 of Fig. 1. Fig. 3 is a sectional view on line 3—3 of Fig. 2. Fig. 4 is a detail perspective view showing the construction of the supporting frame. Fig. 5 is 35 a detail perspective view of another portion of the frame. Fig. 6 is a perspective view of a part of the construction shown in Fig. 5.

Like characters of reference designate 40 similar parts throughout the different figures of the drawing.

In the construction shown the hub of a vehicle wheel is designated at 1 and the spokes thereof at 2. A support is provided 45 and is adapted to be secured to the wheel, preferably adjacent to the hub thereof, and as shown said support is of annular or circular form and surrounds the hub. Said support is indicated as a whole at 3 and is 50 of reversed Z-shaped form in cross-section, a portion 4 thereof being adapted to lie adjacent the spokes and a portion 5 thereof projecting outwardly therefrom and forming with a flange 6 a ball race. The portion 55 4 may be secured to the spokes 2 by means comprising a U-shaped threaded bolt 7 to

the ends of which a spoke engaging clip 8, may be secured, by means of nuts 9. As shown in Fig. 3 the bolt 7 engages and also passes through apertures formed in the portion 4. The support 3 is effectively reinforced and stiffened by flanges 10, 11 and 60 12 and the flange 12 is conveniently provided with an annular groove 13. A retaining member 14 is secured to the support 3 by means which may consist of bolts 15 and said retaining member is provided with a flange 16 which engages said groove 13 to provide a rigid support for said retaining member. Said member 14 is also provided 65 with an annular flange 17 which projects radially outwardly abreast of the support 3 and preferably to a point adjacent the flange 11, for a purpose which will herein- 70 after more fully appear.

A card supporting frame, designated as a whole by 18, is movably mounted on said support 3 and I desirably provide said frame with a bearing member 19 adapted to fit with a working clearance between the 80 portion 5 and the flange 17 and provided with a ball engaging surface 20 adapted to ride upon balls 21 disposed in the ball race. The retaining member 14 serves to retain the bearing member 19 in position and acts 85 therethrough to retain the balls 20 in the race provided therefor. If desired the bearing member 19 may be provided with card attaching means which may consist of a threaded stud 22 and a nut 23, as shown. 90 The bearing member 19 is provided with a peripheral portion of polygonal formation, which may as shown be octagonal and which may be formed by a flange 24.

A skeleton card supporting frame is provided and as shown it consists of a plurality of angularly disposed members secured to each other in interlocking relation and in order to obtain the required lightness of weight and structural rigidity I desirably 100 provide reinforced members of light sheet metal which may be in the form of channel bars 25. As shown each of said bars 25 extends completely across the frame 18, formed thereby, and at points laterally of the center 105 of the frame so that each bar will therefore be slightly reduced in length with respect to the greatest diameter of the frame and the outer ends of said bars are connected with an annular member 26. The disposition of 110 the bars or members 25 forms a central octagonal opening in which the bearing mem-

ber 19 is disposed. The channel bars 25 are conveniently arranged so that their flanges will project inwardly and engage the octagonal perimeter in overlapping relation.

5 It will be obvious that when the frame 18 is built up on the bearing member 19 that the latter will be securely anchored to the frame without the necessity of bolts or screws or other connecting devices.

10 In order to effectively interlock the channel bars 25 with each other for the purpose of providing a rigid frame structure and preventing the frame from "dishing", under lateral pressure, the said bars 25 are disposed in a manner to intersect each other in the manner shown in Fig. 4. Accordingly the base of one channel is apertured to permit an adjacent bar to extend therethrough and the base portion 27 of the extending bar

15 20 engages the wall 28 of the opening or aperture and the flanges 29 of the extending bar engage the wall 30 of the aperture thereby providing a rigid structural engagement of the intersecting bars. It will thus be seen that when the ends of the bars are secured to the annular member 26 their intermediate portions will be rigidly engaged with each other in interlocking relation. In the construction shown each bar 25 will be interlocked with companion bars at four different points. At the intersection of certain of said bars card securing devices 31 may be anchored and will be provided with threaded studs 32 adapted to project through

25 30 35 the card 34 so that the latter may be anchored thereto by means of nuts 33.

The annular member 26 may be formed in one piece with the ends united by a slot and tongue connection 34' and 35, as clearly shown in Figs. 5 and 6.

A buffer of rubber or other suitable material may be provided and as shown said buffer consists of a channel member 36 adapted to inclose the annular member 26, 45 at the rear, and overlap the card 34 at the front. The said buffer will avoid marring the spokes should the frame member be forced inwardly thereagainst.

It will be seen by reference to Fig. 2 that

the parts are so disposed that they will be wholly concealed by the advertising card 34 when the same is viewed from the front.

I claim:—

1. The combination with a vehicle wheel, of an advertising device comprising a support, means for securing said support to the vehicle wheel, and a card supporting frame centrally and rotatively mounted on said support and comprising a plurality of intersecting ribbed bars angularly disposed in interlocking relation with respect to each other.

2. The combination with a vehicle wheel, of an advertising device comprising a support, means for securing said support to the vehicle wheel, a card supporting frame centrally and rotatably mounted on said support and comprising a plurality of reinforced members angularly disposed in interlocking relation with respect to each other, and an annular member connected with the ends of said reinforced members, each of said reinforced members extending across said frame at a point laterally of the greatest diameter thereof and said reinforcing members meeting at said annular member.

3. The combination with a vehicle wheel, of an advertising device comprising a support, means for securing said support to the vehicle wheel, a card supporting frame comprising a plurality of reinforced members angularly disposed in interlocking relation with respect to each other, an annular member connected with the ends of said reinforced members, each of said reinforced members extending completely across said frame laterally of the center thereof to provide a central opening of polygonal formation, and a similarly formed bearing member disposed in said opening and engaged by said reinforced members and rotatably mounted on said support.

In testimony whereof I affix my signature in presence of two witnesses.

JAY PIERRE BERGERON.
